US00D569288S

(12) **United States Design Patent** (10) **Patent No.:** **US D569,288 S**
(45) **Date of Patent:** **** May 20, 2008**

(54) **VISIBLE ELECTRONIC ARTICLE
SURVEILLANCE TAG**

2004/0222890 A1 * 11/2004 Yang et al. 340/572.9
2005/0270161 A1 * 12/2005 Yang et al. 340/572.9

(75) Inventor: **Dale W. Raymond**, Boca Raton, FL
(US)

* cited by examiner

(73) Assignee: **Sensormatic Electronics Corporation**,
Boca Raton, FL (US)

Primary Examiner—Elizabeth A. Albert
Assistant Examiner—Kelley A Donnelly

(**) Term: **14 Years**

(21) Appl. No.: **29/207,250**

(22) Filed: **Jun. 10, 2004**

(51) **LOC (8) Cl.** **10-05**

(52) **U.S. Cl.** **D10/104**

(58) **Field of Classification Search** D10/106,
D10/104; 340/572.9, 572.8, 506, 551; 24/326
See application file for complete search history.

The ornamental design for the visible electronic article surveillance tag, as shown.

CLAIM

DESCRIPTION

FIG. 1 is an upper oblique angle view of the new design.

FIG. 2 is another upper oblique angle view of the new design.

FIG. 3 is a lower oblique angle view of the new design.

FIG. 4 is another lower oblique angle view of the design.

FIG. 5 is an oblique angle view of another portion of the new design.

FIG. 6 is a top view of a portion of the new design.

FIG. 7 is a top view of another portion of the new design.

FIG. 8 is a profile view of a portion of the new design.

FIG. 9 is a profile view of another portion of the new design.

FIG. 10 is an end view of a portion of the new design; and,

FIG. 11 is an end view of another portion of the new design.
The circular button portion shown in broken lines in FIGS. 5 and 7-11 forms no part of the claimed design.
